CLAIM

The ornamental design for a pick holder, as shown and described.

DESCRIPTION

FIG. 1 is a perspective view of my pick holder according to my new design;

FIG. 2 is a front view thereof;

FIG. 3 is a rear view thereof;

FIG. 4 is a right, side view thereof;

FIG. 5 is a left, side view thereof;

FIG. 6 is a top view thereof; and,

FIG. 7 is a bottom view thereof.

Conventional shading is applied to illustrate the contours of the design and does not represent surface ornamentation. The broken lines illustrate the design as used and form no part of the claimed design.
